UNITED STATES PATENT OFFICE

115,762

DESIGN FOR A BRASSIÈRE

Samuel Green and Herman Miller,
New York, N. Y.

Application April 20, 1939, Serial No. 84,416

Term of patent 3½ years

To all whom it may concern:

Be it known that we, Samuel Green and Herman Miller, citizens of the United States, both residing in the county, city, and State of New York, have invented a new, original, and ornamental Design for a Brassière, of which the following is a specification, reference being made to the accompanying drawing, forming a part thereof.

Fig. 1 is a front view of a brassière incorporating the invention;

Fig. 2 is a rear view thereof; and

Fig. 3 is a side view thereof.

We claim:

The ornamental design for a brassière, substantially as shown.

HERMAN MILLER.
SAMUEL GREEN.
